SELF-ADJUSTING HAT FITTING APPLIANCE
AND THE LIKE

Charles Doering, Chicago, Ill.

Application February 7, 1942, Serial No. 429,863

4 Claims. (Cl. 2—183)

This invention relates to hat fitting appliances and more particularly to self-adjusting hat sizing devices, although certain features thereof may be applied with equal advantages for other purposes.

It contemplates more especially the provision of an attachment that will conform a hat to the head of the wearer irrespective of substantial variations in their respective size.

One object of the present invention is to simplify the construction and improve the operation of devices of the character mentioned.

Another object is to provide a pair of resilient confronting members of relatively different arcuate configuration to serve as a hat conforming device.

Another object is to provide a pair of resilient confronting members of relatively different arcuate configuration with displaceable free portions to serve as a hat conforming device responsive to its placement on the head of the wearer.

A further object is to provide relatively curved resilient members in confronting operative relation so that both will yield relative to each other to conform a hat to the head of the wearer.

A still further object is to provide confronting resilient members with relatively curved contours so that one will yield relative to the other to conform a hat to a substantially smaller head.

Still a further object is to provide relatively curved resilient bands anchored to each other to provide free extremities relatively displaceable responsive to imparting pressure thereto incident to the placement of a hat upon the head of a wearer.

Other objects and advantages will appear from the following description of an illustrative embodiment of the present invention.

In the drawing:

Figure 1 is an edge view of a device embodying features of the present invention.

Figure 2 is the front view in elevation of a device shown in Figure 1.

Figure 3 is a front view in elevation of a hat having a device embodying features of the present invention shown in dotted outline in operative association therewith.

Figure 4 is a fragmentary sectional view taken substantially along line IV—IV of Figure 3.

Figure 5 is a fragmentary sectional view conforming to Figure 4 but showing a slightly modified embodiment of the invention.

Figure 6 is a fragmentary front view in elevation of an extremity of the modified device 55

shown in Figure 5, to illustrate the band attaching expedient for the hat fitting appliance.

The structure selected for illustration comprises a substantially rectangular plate 10 preferably though not essentially stamped or otherwise shaped from resilient material such as spring steel, bronze, Celluloid or plastics to impart thereto a normal arcuate configuration (Figure 1) to present a substantially convex bow which is of considerably shorter radii than the average head of the wearer. The rectangular band 10 is an elongated shape with the convex bow normally provided therein to assume a curved position which would be too small for the range of heads for which hats, caps, or other headgear may be provided. In other words, the extremities 11 and 12 of the band 10 would normally engage the head with the intermediate bowed portion projecting substantially therefrom. The relative position of the head to the normal shape of the elongated band 10 may be conveniently represented by the arcuate dotted line 13 (Figure 1). The range of head sizes would be such that the elongated band 10 in its normal position 25 would never establish full contact with the head of the wearer.

In order to render the elongated member 10 more effective to adapt a larger hat, cap, or other headgear 14 to a substantially smaller head size 30 13, another elongated band 15 of substantially greater curvature than the band 10, is operatively associated in confronting relation therewith. To this end, the more highly curved band 15 has substantially shorter radii than the band 10, and is operatively associated therewith in any suitable manner. In the present embodiment the band 15 is anchored proximate to one extremity 16 to a corresponding end 12 of the band 10 by any suitable fastening expedient such as 40 spot-welding 17.

It should be noted that the band 15 is superposed upon band 10 and anchored proximate to the extremity 12 of the latter for superposed alignment so that normally the free extremity 18 of the outer band 15 will terminate appreciably short of the extremity 11 of the inner band 10. As a result, any radial stress imparted between the inner and outer bands 10—15 will cause the latter or superposed band 15 to flex 50 substantially and assume the curvature of the inner band 10 as shown in dotted outline in Figure 1.

This is the initial step of conformance between the hat and head of the wearer to constitute a take-up in the event the variation be-

tween the head and hat size does not constitute a full size. In other words, where there is little variation between the head and hat the upper band 15 may conform fully. Any increased stress occasioned by even a smaller variation between the actual head and the hat size will tend to flex an inner band 10 and cause it to conform further to the head of the wearer in the event the relative variation therebetween does not exceed a fractional size. In other words, the confronting inner and outer bands 10-15 may be shaped and sized to serve as a take-up between the hat and the head of a full size or more, but there may be variations within a wide range depending upon the dictates of commercial practice as to the limit of take-up that shall be prescribed for any particular set of inner and outer bands 10-15 or a single band.

The superposed bands 10-15 are preferably though not essentially inserted between the inner hat band 19 and the crown 20 of the hat, cap, or other headgear 14 (Figures 3 and 4). To preclude movement of the superposed bands 10-15, it may be desirable to provide apertures 21-22 proximate to the extremities 11-12 of the inner band 10. This will enable the attachment of the inner band 10 with its outer band 15, to the hat band 19 by any suitable fastening expedients such as brads 23 that project therethrough for attachment to the inner hat band 19 in a manner known with standard fasteners. Additionally, to preclude relative movement between the hat 14 and the outer band 15, a series of indentations providing corresponding projections 24 may be provided in the outer bands 15 to become impressed in the relatively soft material from which the crown 20 is made.

In the modified embodiment shown in Figures 5 and 6 the inner flexible hat band 10' has both extremities 11'-12' provided with normally disposed offsets 21'-22' anchored thereto in any suitable manner such as by spot-welds 23'. The offsets 21' terminate in reversely bent flanges 24' that are adapted to engage over the peripheral edge 25 of the inner hat band 19' in order to retain the flexible inner and outer bands 10'-15' in their operative position between the inner hat band 19' and the crown 20'. Indentations 26 may be provided in the flanged portion 24' of the offsets 21' in order to frictionally engage peripheral region 25 of the inner hat band 19'. This affords a temporary attaching medium for the hat fitting device. This is of primary significance in connection with military service hats where duplication would be undesirable because of the large number that would be utilized in the event such was adopted as standard military equipment. It should be noted that a very simple, flexible, and highly advantageous device has been provided to conform large hats to appreciably smaller heads in situations where the supply of exact sizes would be impractical.

It should be emphasized that while invention has been described particularly in connection with headgear, it can be utilized with equal advantage as a waistband compensator in conjunction with trousers in order to conform them to the shape of the body and thus do away with

a belt. In a modified form when sized for the particular purpose, the structure can be used on any kind of socks or stockings, ladies' or men's, to conform with the shape of the leg and hold the apparel in position. Likewise, the device in a somewhat modified form to meet the special purpose on men's vests to do away with a buckle, and at the same time to conform the vest to the body and form a better shaped vest on the person. In a considerably reduced size, the device can be used as a safety for a ring which is worn on the finger by conforming to three or four different sizes so that the ring cannot be taken off the finger. It keeps the ring from turning and in the initial position.

These examples should be construed merely as illustration rather than limitation upon the invention in that various changes may be made in the embodiment of the invention herein specifically described without departing from the invention or sacrificing any of the advantages or features thereof, and nothing herein shall be construed as a limitation of the invention, its concept or structural embodiment as to the whole or any part thereof except as defined in the appended claims.

I claim:

1. A self-adjusting device for headgear and the like comprising an arcuate resilient elongated band bowed to normally possess shorter radii than the human head for adapting a larger size headgear thereto, and friction means for removably attaching said band to the headgear in a position to confront the head of the wearer, said elongated normally bowed band being substantially shorter than the circumference of the headgear and detachably associated therewith.

2. A self-adjusting device for headgear and the like comprising an arcuate resilient elongated band bowed to normally possess shorter radii than the human head for adapting a larger size headgear thereto, and another elongated bowed resilient band anchored to said first named band to cooperate therewith as a take-up between the headgear and head of the wearer.

3. A self-adjusting device for headgear and the like comprising an arcuate resilient elongated band bowed to normally possess shorter radii than the human head for adapting a larger size headgear thereto, and another elongated bowed resilient band anchored at one extremity to a corresponding extremity of said first named band to cooperate therewith as a take-up between the headgear and head of the wearer.

4. A self-adjusting device for headgear and the like comprising an arcuate resilient elongated band bowed to normally possess shorter radii than the human head for adapting a larger size headgear thereto, and another elongated bowed resilient band anchored at one extremity to a corresponding extremity of said first named band to cooperate therewith as a take-up between the headgear and head of the wearer, said last named band having a greater curvature than said first named band to comprise a compound take-up therewith.

CHARLES DOERING.
